UNITED STATES PATENT OFFICE.

ALEK KISS, OF FLINT, MICHIGAN.

BUILDING CONSTRUCTION.

Application filed April 18, 1925. Serial No. 24,100.

To all whom it may concern:

Be it known that I, ALEK Kiss, a citizen of Hungary, residing at Flint, in the county of Genesee and State of Michigan, have invented certain new and useful Improvements in Building Constructions, of which the following is a specification.

This invention relates to improvements in building construction.

10 The primary object of the invention is the provision of an improved wall structure suitable for forming the outside or partition walls of a building.

15 A further object of the invention is the provision of means suitable for connecting molded or pressed building blocks, without the use of a binding agent, such as mortar, cement, etc., to form a wall structure, said means being further suitable for having finishing laths or the like fastened thereto.

20 Other objects and advantages of the invention will be apparent during the course of the following description.

25 In the accompanying drawings forming a part of this specification and in which like numerals are employed to designate like parts throughout the same,

30 Figure 1 is a fragmentary side elevational view of a building wall under construction, Figure 2 is a top plan view of the walls of a two room building and shows the improved method of constructing walls or the like which embodies this invention;

35 Figure 3 is a vertical sectional view of a building wall embodying the features of construction constituting this invention,

40 Figure 4 is a perspective view of one of the building blocks employed for forming an outside wall,

45 Figure 5 is a perspective view of the type of building block employed for forming a partition wall,

Figure 6 is a modified form of building block,

50 Figure 7 is a fragmentary perspective view of an upright with the inside building block holding strips fastened thereto;

55 Figure 8 is a fragmentary perspective view of an outside block locking board, and

Figure 9 is a fragmentary perspective view of an inside block holding strip.

Referring to the accompanying drawings and particularly to Fig. 1, wherein for the purpose of illustration is shown a preferred embodiment of this invention, the numeral 5 designates a foundation for a building wall which is formed of bricks 6 having their outer faces ornamented or decorated, as at 7. Mounted upon the top face 5^a of the foundation 5 is a baseboard 8 formed with a longitudinally extending groove 9 in its top face. Fastened to the top face of this baseboard 8 are a desired number of uprights 10, preferably of wood, which are fastened at their lower ends by the angularly driven nails 11. These uprights 10 are intended to extend in parallelism with each other and to be spaced a distance equal to the length of the building blocks 12.

Before arranging the building blocks 12, 70 in the positions shown in this figure, the uprights 10 have fastened thereto the longitudinally extending, inside block holding strips 13 which are fastened to the side faces of the uprights 10 at their inner longitudinal edges and have the fastening nails 14 driven through the strips to the sides of the said uprights. The building blocks 12 may then be positioned between the adjacent uprights 10 and arranged so that the inside 75 holding strips 13 will be received within the inner rabbeted edges 15 of the blocks. It will now be seen that the blocks will cover the fastening nails 14 and will prevent the withdrawal of the same. To complete the 80 fastening of the blocks 12 in place, the outside locking boards 16 should be fastened to the outer longitudinal edges of the uprights 10, by the fastening nails 17 driven into the edges of the uprights. It will be seen that 85 these locking bolts 16 are received at their edges in the rabbeted edges 18 of the building blocks 12 so that the outer faces of the blocks and boards will lie in a common 90 plane.

95 The blocks 12 are formed at their opposite ends with tongues and grooves 19 and 20, as illustrated in the various figures, the

tongues 19 of the lowest bricks being received within the groove 9 formed in the base board 8 while the remaining blocks have their tongues received in the blocks 5 immediately below the same.

Figure 1 shows the metal lath 21 fastened to the outside locking boards 16 by the nails or staples 22. This metal lath 21 will permit the plaster, stucco, or the like, 23 to 10 be fastened to the outer face of the wall for finishing the same to produce a very pleasing appearance. It will be understood that the inner longitudinal edges of the uprights 10 are suitable for having either metal or 15 wooden laths fastened thereto for receiving plaster or other finishing material.

In Fig. 2 there is shown in plan the various walls of a building. The outer walls are constructed in the manner just described. The partition 24 is formed in substantially the same way but from the partition blocks 25 which are preferably thinner or of less thickness than the building blocks 12. These partition blocks 25 are 25 formed with the rabbeted edges 26 and have a tongue formed on one end and a groove 27 formed in the other end, the tongue not being shown in Fig. 5 wherein a detail view of a partition block 25 is shown. The uprights 28 have fastened thereto block holding strips 29 and block locking boards 30 in the same manner as described in connection with the strips and boards 13 and 16 shown in Fig. 1.

35 The opposite end faces of the partition wall 24 are illustrated as being connected to the outside walls in two different manners. In one form, the upright 28 abuts against the inner longitudinal edge of an upright 10 and has a locking board 30 terminating with one edge flushly engaging the outer face of a block holding strip 13. In the other form, the upright 28 engages an upright 10 in the same manner, but one of 40 the inside holding strips 13 is omitted and the locking board 30 carried by the upright 28 is projected into the rabbeted edge 15 of the building block 12. This is believed to be the preferred form as it more rigidly 45 anchors the partition wall to the outside wall.

50 This Figure 2 shows the preferred way of forming a corner of a building which is to fasten two uprights 10 with their adjacent side faces abutting each other, as shown. The inside holding strips 13 are mounted on the inner faces of the inner upright 10 in close proximity to the inner longitudinal edge of that upright. The outer faces of the two uprights 10 are provided with locking boards 16 which enter the outer rabbeted edges 18 of the adjacent blocks 12.

55 In Fig. 3 the overlying building blocks 12 are illustrated as having a binding agent 31 positioned between the same. Such a

binding agent may be used if desired, but it is considered that the same is unnecessary, as relative movement between the building blocks is prevented by the uprights and their holding strips and locking boards. 70 This figure further illustrates the foundation 5 as being seated upon a cement or cinder bed 32. It is to be understood that any desired mounting may be used for this type of foundation. 75

In Fig. 6 there is shown a modified form of building block which may be used in place of the outside blocks 12 or partition blocks 25. This modified form of building block includes the body portion 33 having the various rabbeted edges 34 and 35. The rabbeted edges 35, it will be noticed, are at diagonally opposed edges while the rabbeted edges 34 are formed in the same side of the body 33. 80

85 It is to be understood that the forms of this invention herewith shown and described are to be taken as preferred examples of the same, and that various changes in the shape, size, and arrangement of parts may be resorted to without departing from the spirit of the invention or the scope of the subjoined claims.

90 The building blocks 12, 25 and 33, shown in detail in Figs. 4 to 6, are intended to be formed from a plastic mixture consisting of cement 20%, slate cinders 70%, and ashes of slate cinders 10%. 95

Having thus described the invention, I 100 claim:—

1. In a building construction, a wall consisting of a baseboard, a plurality of uprights fastened to said baseboard, a vertical row of blocks positioned between each adjacent pair of uprights, said blocks having their vertical edges rabbeted, holding strips fastened to the uprights and received within the inner rabbeted edges of the rows of bricks, locking boards fastened to the outer faces of the uprights and projecting laterally into the outer rabbeted edges of the rows of blocks, and a finishing coat fastened to the locking boards. 105

110 2. In a building construction, a wall consisting of a baseboard, a plurality of uprights fastened to said baseboard, a vertical row of blocks positioned between each adjacent pair of uprights, said blocks having their vertical edges rabbeted, holding strips fastened to the uprights and received within the inner rabbeted edges of the rows of blocks, locking boards fastened to the outer faces of the uprights and projecting laterally into the outer rabbeted edges of the rows of blocks, lathing fastened to the locking boards, and a finishing coat placed upon said lathing. 115

120 3. In a building construction, a wall consisting of a baseboard, a plurality of uprights fastened to said baseboard, a vertical 125

row of building blocks positioned between each adjacent pair of uprights, said blocks having their vertical edges rabbeted, holding strips fastened to the uprights by nails driven horizontally into the latter, said holding strips being received within the inner rabbeted edges of the rows of blocks with the said blocks covering the heads of

said fastening nails, and locking boards fastened to the outer longitudinal faces of 10 the uprights and projecting laterally therefrom to be received within the outer rabbeted edges of the rows of blocks.

In testimony whereof I affix my signature.

ALEK KISS.
